MINIATURE GOLF GAME BOARD

Carl Max Maurer, Nurnberg, Germany, assignor to Kartonax G.m.b.H., Nurnberg, Germany

Filed Aug. 14, 1961, Ser. No. 66,331

Term of patent 14 years

(Cl. D34—5)

Fig. 1

Fig. 2

FIG. 1 is a plan view of the miniature golf game board;

FIG. 2 is a front elevational view of FIG. 1;

FIG. 3 is an end view of FIG. 1; and

FIG. 4 is a perspective view of the miniature golf game board.

The dominant features of my design reside in the portions shown in full lines. The game balls shown in broken lines are for illustrative purposes only.

I claim:

The ornamental design for a miniature golf game board, as shown and described.
